US00D745765S

(12) **United States Design Patent**
Mikolajczyk et al.

(10) **Patent No.:** **US D745,765 S**
(45) **Date of Patent:** **** Dec. 15, 2015**

(54) **CLUSTER BOX MAIL DELIVERY UNIT**

(71) Applicant: **The United States Postal Service**,
Washington, DC (US)

(72) Inventors: **Ryszard K. Mikolajczyk**, Chicago, IL
(US); **Taurris D. Baskerville**,
Schaumburg, IL (US)

(73) Assignee: **United States Postal Service**,
Washington, DC (US)

(**) Term: **14 Years**

(21) Appl. No.: **29/492,725**

(22) Filed: **Jun. 2, 2014**

Related U.S. Application Data

(63) Continuation of application No. 14/170,398, filed on
Jan. 31, 2014, now Pat. No. 8,973,812, which is a
continuation of application No. 11/168,471, filed on
Jun. 29, 2005, now Pat. No. 8,661,862.

CLAIM

The ornamental design for a cluster box mail delivery unit, as shown and described.

DESCRIPTION

FIG. 1 is a perspective view of a cluster box mail delivery unit showing our new design;

FIG. 2 is a front view thereof;

FIG. 3 is a right side view thereof;

FIG. 4 is a left side view thereof; and,

FIG. 5 is a top view thereof.

The back view and bottom view form no part of the claimed design.
